UNITED STATES PATENT OFFICE.

MARCEL URBAIN CAILLAU, OF BILLANCOURT, FRANCE.

COUPLING CLIP.

Application filed December 31, 1923. Serial No. 683,732.

To all whom it may concern:

Be it known that I, MARCEL URBAIN CAILLAU, a citizen of the French Republic, residing at Billancourt, Seine, France, have invented new and useful Improvements in Coupling Clips, of which the following is a specification, reference being had therein to the accompanying drawings.

The present invention relates to new and useful improvements in coupling clips.

It has previously been proposed to provide coupling clips or collars comprising a metallic band or ligature held at one of its ends around the two juxtaposed ends of a metallic shackle, such shackle having in blank form a rectangular link shape and being bent back upon itself so as to present two symmetrical opened out portions or loops through which a winding split pin is inserted, the said metallic band or ligature being bent around the mutually overlying ends of the said shackle and firmly clamped thereagainst. In using such clips, one end of the band is bent around the two juxtaposed ends of the shackle and is then bent back upon itself, as above stated. The remaining or greater portion of the said band is afterwards passed once or twice, according to practical requirements, around the coupling sleeve and its free end is inserted through the slot in the winding pin, there now only remaining to rotate the said pin to the desired extent to draw the said band tightly upon the said sleeve and thereby ensure the coupling of the articles that it connects. The band or ligature having thus been tightened up, the winding pin remains substantially stationary thus ensuring the invariable coupling of the said articles.

Now, the present invention has reference to new and useful improvements in the above described coupling clips, such improvements superseding the split winding pin as above referred to by a cylindrical slotted winding pin with a view to eliminating certain drawbacks consequent upon the use of such split pins when utilizing clips of the above described type.

A primary feature of the improved winding pin according to the invention resides in its being somewhat larger in diameter than the inner diameter of the loops of the shackle so as to be capable when it is being inserted therethrough, to slightly force

apart the two overlying ends of said shackle, for a purpose to be described hereinafter.

A further feature of this improved winding pin resides in its being provided with a diametrically arranged and outwardly flaring slot only extending over a predetermined part of its length from one of its ends and sufficiently long to permit said slot to register with the opened out portion of the shackle when the said pin is in proper position therein, for a purpose to be described hereinafter.

A still further feature of this improved pin resides in the fact that it is advantageously formed in its non-slotted end with an enlarged cylindrically, prismatically or spherically shaped head, the latter being pierced with a suitably sized round hole at right angles to the slot alluded to, also for a purpose to be described hereinafter.

A still further feature of this improved winding pin resides in the fact that the outer or top face of its head is formed with a diametrical groove, also for a purpose to be described hereinafter.

A still further feature of this improved winding pin resides in its slotted end, opposite to the one provided with the enlarged head, being rounded for facilitating the insertion thereof through the looped part of the shackle.

By using a cylindrical winding pin presenting the above mentioned features in coupling clips pertaining to the type as above referred to, the following advantages are secured:

The winding pin is firmly retained within the shackle in the proper position without necessitating any nuts, screws or other locking members, and may be released as often as required from the articles that it couples without requiring the unrolling or uncurling of the metallic band or ligature, merely by pulling the winding pin out of the looped part of the shackle after having slightly unwound it. The clip may afterwards be tightened again upon the articles to be re-coupled merely by the sequence of the operations described, but in an inverse order.

In the accompanying drawing is illustrated the improved coupling clip and pin embodying the invention and the manner of utilizing it for coupling two pipe sections.

Fig. 1 is a longitudinal elevation of the

winding pin showing its longitudinally disposed slot and its enlarged head of prismatical shape.

Fig. 1^a is a longitudinal elevation of same, according to two modifications, showing the pin deprived of any enlarged head and the winding pin provided with a spherical head, respectively.

Fig. 2 shows the two ends of the pin.

10 Fig. 3 shows the centrally opened out blank for making the shackle, assuming same to be lying on the flat.

Fig. 4 shows such shackle in its bent over form in elevational and edge views respectively.

15 Fig. 5 shows the whole of the clip, the end of the metallic band being bent back upon itself around the two overlying ends of the shackle but not yet curled upon itself.

20 Fig. 6 is a perspective illustration of the first curling phase of the band.

Fig. 7 is a perspective view of the clip, on completion of the second curling phase of its band.

25 Fig. 8 is a perspective view of the method used for passing such a metallic band around the sleeve connecting two pipe sections.

Fig. 9 is an edge view of the whole clip showing how its band is curled and held in 30 position.

a designates the cylindrically shaped winding pin, according to the invention. Said pin is provided with a diametrical slot *b* extending therethrough from one of its 35 ends and as far as a position *c* situated at a short distance from the head *e*. As clearly illustrated, the outermost portion of said slot *b* is flared outwardly as at *d*. The head *e* of the pin may be cylindrically, prismatically or spherically or even otherwise suitably shaped according to the requirements. It is pierced with a hole *f* extending therethrough at right angles to the slot *b*. This 40 hole *f* is adapted for receiving the tail portion of a tool *D* (see Fig. 8) for the purpose of rotating the pin *a* and thus winding up or unwinding (as the case may be) the clip, as will appear hereinafter. The head *e* is moreover formed on its outer or top face 45 with a diametrical groove *g* adapted for receiving the bit of a screw-driver or similar tool also for the purpose of rotating the pin.

The shackle is obtained by bending upon itself substantially midway of its length a 50 rectangular metallic blank plate *lm* opened out centrally to form a rectangular opening *o* the size of which is reckoned so as to give the perimetral margin of the said blank a uniform width and consequently an even resistance all around. The bending of the shackle 55 upon itself is effected so as to give same in edge view the peculiar shape shown in Fig. 4, the loops *n* being adapted for receiving the winding pin.

60 As above stated, the diameter of the pin *a*

is slightly greater than the inner diameter of both loops *n*, whereby when inserting said pin within said loops, the overlying ends *l* of the shackle are slightly forced apart (as shown in Fig. 4).

70

In using the clip, one end of the metallic band *a* intended for constituting the ligature is passed through the space *h* between the pin *a* and the ends *l* of the shackle and then bent back upon itself around the said 75 ends *l* so that its extremity *A'* should be positioned slightly beyond thereto, as clearly illustrated in chain lines in Fig. 4.

When it is desired to couple together two articles, for instance two pipe sections *E E'* 80 of equal diameter (see Fig. 8), their adjacent ends must first of all be wrapped up within a sleeve *C*, made of india rubber or the like, which sleeve is afterwards ligatured by means of the improved clip according to the invention.

85

As clearly illustrated in Fig. 6, after the first curling of the band *A*, its free extremity *k* is passed through the space *h* and then passed or curled a second time around 90 the article, after which the said extremity *k* is inserted through the slot *b* in the pin *a*, the protruding tongue being cut off. By then rotating the pin *a*, either by introducing the tail of a tool *D* (see Fig. 8) into its 95 hole *f*, or by gripping its prismatical head *e* within the jaws of a spanner, or else by inserting the bit of a screw-driver or similar tool in the groove *g*, it becomes possible to wind up the said pin *a* and thus to strongly 100 tighten the two curls of the band *A* around the sleeve *C* or equivalent member. During the rotation of the pin *a*, as above described, as the band *A* wraps up the two 105 overlying ends *b* of the shackle, said ends are pressed together, thus slightly lessening the inner diameter of the loops *n* which in turn exert a braking action upon the pin *a*. Furthermore, the band *A* owing to its 110 engagement with the outer periphery of said pin becomes slightly creased, such crease ensuring its retention in proper position. The friction exercised by the two curls of the band also assists in clamping same in position around the coupling sleeve *C* or equivalent member.

115

As the slot only extends over a portion of a length of the pin *a* so as to register with the opened out portion of the shackle, when the band is being tightened up, as above 120 described, the two halves of the said pin become more closely held together whereby their resiliency tending to force them apart also assists in exerting a braking action upon the pin *a*.

125

Moreover, as the pin *a* is cylindrically shaped, its rotation within the loops *n* can not distort it, as a result of which the release of the clip may conveniently be performed without uncurling the band *A*, it 130

only being sufficient to slightly unwind the pin *a* (by any of the above enumerated ways). The unwinding of the pin then stops the braking action referred to whereby the pin slot *b* resumes its normal width and makes it possible to pull the pin out of engagement with the loops *n*. When afterwards it is desired to re-introduce the pin in its proper position with a view to re-winding up the band or ligature, all that is necessary is to thrust the said pin into the loops *n*. As the outer end of the slot *b* is flared outwardly, the engagement of the band in such slot is facilitated particularly inasmuch as said band then occupies the twisted position *p* illustrated in Fig. 9.

From the foregoing, it will be apparent that, for use on coupling clips of the type hereinbefore specified, a slotted, cylindrical winding pin is provided which obviates the several drawbacks inherent to split winding pins, whilst permitting a much more efficient and durable coupling to be ensured.

It must be understood that the form of this winding pin herewith shown and described is to be taken as the preferred embodiment of the invention and that minor changes in the arrangement of the said pin may be resorted to without departing from the spirit of the invention or the scope of the subjoined claims.

What I claim and desire to secure by Letters Patent is:—

1. The combination with a coupling clip having a looped shackle of the type set forth, of a winding pin having a diameter slightly greater than the inner diameter of the loops of said shackle, so that the loops of said shackle will be forced to expand and grip said winding pin upon insertion thereof into the loops of said shackle, and a diametrical slot in said winding pin extending from one of its ends a predetermined portion of its length.

2. The combination with a coupling clip having a looped shackle of the type set forth, of a winding pin having a rounded end and a diameter slightly greater than the inner diameter of the loops of said shackle so that the loops of said shackle will be forced to expand and grip said winding pin upon insertion thereof into the loops of said shackle, and a diametrical slot in said winding pin extending from one of its ends a predetermined portion of its length.

3. The combination with a coupling clip having a looped shackle of the type set forth, of a winding pin having a diameter slightly greater than the inner diameter of the loops of said shackle so that the loops of said shackle will be forced to expand and grip said winding pin upon insertion thereof into the loops of said shackle; a diametrical slot in said winding pin expanding from

one of its ends a predetermined portion of its length; and a head on said winding pin at the end opposite said slotted portion.

4. The combination with a coupling clip having a looped shackle of the type set forth, of a winding pin having a diameter slightly greater than the inner diameter of the loops of said shackle so that the loops of said shackle will be forced to expand and grip said winding pin upon insertion thereof into the loops of said shackle; a diametrical slot in said winding pin extending from one of its ends a predetermined portion of its length; and an aperture in said winding pin at right-angles thereto and remote from said slot.

5. The combination with a coupling clip having a looped shackle of the type set forth, of a winding pin having a diameter slightly greater than the inner diameter of the loops of said shackle so that the loops of said shackle will be forced to expand and grip said winding pin upon insertion thereof into the loops of said shackle; a diametrical slot in said winding pin extending from one of its ends a predetermined portion of its length; a head on said winding pin at the end opposite said slotted portion; and an aperture in said head at right-angles to said slot.

6. The combination with a coupling clip having a looped shackle of the type set forth, of a winding pin having a diameter slightly greater than the inner diameter of the loops of said shackle so that the loops of said shackle will be forced to expand and grip said winding pin upon insertion thereof into the loops of said shackle, and a diametrical slot in said winding pin flaring out at its end, extending a predetermined portion of its length.

7. The combination with a coupling clip having a looped shackle of the type set forth, of a winding pin having a rounded end and a diameter slightly greater than the inner diameter of the loops of said shackle so that the loops of said shackle will be forced to expand and grip said winding pin upon insertion thereof into the loops of said shackle; and a diametrical slot in said winding pin extending from said rounded end a predetermined portion of its length, said slot being flared outwardly at said rounded end and having a width slightly greater than the thickness of the metallic band forming the coupling clip.

8. The combination with a coupling clip having a looped shackle of the type set forth, of a winding pin having a diameter slightly greater than the inner diameter of the loops of said shackle so that the loops of said shackle will be forced to expand and grip said winding pin upon insertion thereof into the loops of said shackle; a diametrical slot in said winding pin extending

from one of its ends a predetermined portion of its length; and a head on said winding pin at the end opposite said slotted portion having a slot formed in the top face thereof.

- 5 9. The combination with a coupling clip having a looped shackle of the type set forth, of a winding pin having a diameter slightly greater than the inner diameter of the loops of said shackle so that the loops of said shackle will be forced to expand and grip said winding pin upon insertion thereof into the loops of said shackle; a diametrical slot in said winding pin extending from one of its ends a predetermined portion of its length, and a prismatically shaped head on said winding pin.
- 10 10. The combination with a coupling clip having a looped shackle of the type set forth, of a winding pin having a rounded

end and a diameter slightly greater than the inner diameter of the loops of said shackle so that the loops of said shackle will be forced to expand and grip said winding pin upon insertion thereof into the 25 loops of said shackle; a diametrical slot in said winding pin extending from said rounded end a predetermined portion of its length, said slot being flared outwardly at said rounded end and having a width 30 slightly greater than the thickness of the metallic band forming the coupling clip; a head on said winding pin opposite to said rounded end; an aperture in said head at right-angles to said slot; and a diametrical 35 slot formed in the top face of said head.

In testimony whereof I have signed my name to this specification.

MARCEL URBAIN CAILLAU.
